(57) **CLAIM**

The ornamental design for a mount for electronic device, as shown and described.

DESCRIPTION

FIG. 1 is a front isometric view of a first embodiment of a mount for electronic device showing our new design; FIG. 2 is a rear isometric view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a front isometric view of a second embodiment of a mount for electronic device; and,

FIG. 10 is a rear isometric view thereof.

The broken lines depict unclaimed environment. The broken lines form no part of the claimed design.
